UNITED STATES PATENT OFFICE.

ARTHUR L. LEWIS, OF ROCHESTER, AND JOHN L. TURNER, OF MONACA, PENNSYLVANIA.

METAL-BENDING MECHANISM.

1,254,516.

Specification of Letters Patent. Patented Jan. 22, 1918.

Application filed February 6, 1917. Serial No. 146,942.

To all whom it may concern:

Be it known that we, ARTHUR L. LEWIS and JOHN L. TURNER, citizens of the United States, residing at Rochester and Monaca, respectively, in the county of Beaver and State of Pennsylvania, have invented certain new and useful Improvements in Metal-Bending Mechanisms, of which the following is a specification.

10 This invention contemplates certain new and useful improvements in metal bending mechanisms and relates more especially to an improved device for bending flat plates or "skelp" into tubular shapes.

15 The present invention has for an object the production of a tube forming mechanism in which the "skelp" from which the tube is formed is successively treated by relatively positioned forming devices, said devices being co-operatively associated with a bending die through which the skelp is drawn.

20 Another object of this invention is to produce a tube forming mechanism including among other things a bending die or shaping trough, a plurality of co-operating tube forming devices adjustably positioned with relation to the said bending die and to each other, the said co-operating tube forming devices comprising a movable blow member arranged to give an initial curvature to the skelp, and a movable tube forming device or "pipe ball" around and over which the skelp is drawn as it passes through 25 the bending die.

30 A further object of this invention is the production of a tube forming mechanism including in combination a bending die or shaping trough, a co-operating tube forming device over which the skelp is drawn, and means for positively lowering and raising the said tube forming member with relation to the bending die.

35 A still further object of the present invention is to produce a tube forming mechanism including in combination a bending die or shaping trough, a plurality of co-operating tube forming devices, movable into and out of the said bending die, positive 40 guiding mechanism for the said devices, means including positively operated pistons connected to the said tube forming devices for the raising and lowering thereof, and

additional means for retracting one of said tube forming devices from within the bending die. 55

With these and other objects in view the invention further consists in the arrangement and combination of the several mechanisms hereinafter described and pointed out 60 in the appended claims.

In the drawings which show by way of illustration an embodiment of our invention;

Figure 1 is a side elevation of our improved tube forming mechanism, a portion 65 of a conventional skelp drawing mechanism being shown applied thereto.

Fig. 2 is an end elevation thereof, the skelp drawing mechanism being removed.

Fig. 3 is an enlarged sectional elevation 70 showing the relative positions of the tube forming devices, at one stage of the operation as the skelp is being drawn through the bending die.

Fig. 4 is a fragmentary plan view, illustrating the means of adjustment of the cylinders which contain the pistons carrying the tube forming devices. 75

Figs. 5 and 6 are detail horizontal sectional views on the lines 5—5 and 6—6, respectively, of Fig. 1, further showing the relative adjustment of the cylinders. 80

Fig. 7 is a detail sectional end elevation on the line 7—7 of Fig. 1 showing the supporting means for the cylinders. 85

Fig. 8 is an enlarged sectional view of one of the tube forming devices; and,

Fig. 9 is a detail vertical sectional view on the line 9—9 of Fig. 3.

The present invention has been primarily 90 designed to facilitate the production of metal pipe or tubing. In the producing of metal pipe or tubing it is usual to draw the flat plate or skelp through a bending die and over a suitable tube forming device 95 which is positioned within the bending die as the skelp is drawn therethrough. The positioning of the tube forming device is now largely a matter of manual labor. The initial treating of the skelp in giving it a 100 slight bend when it is fed into the entrance end of the bending die is also a matter of manual labor, it being usual for two men to sledge this curvature into the skelp. To overcome these laborious operations, the 105 present invention has been produced wherein

a highly efficient mechanism is provided for accomplishing advantageously and economically the desired objects.

Referring to the drawings, the invention 5 comprises a suitable bending die or shaping trough 1 mounted upon the base 2. This bending die may be of the usual flaring or bell shape and is slotted at the bottom to accommodate the insertion of the gripping 10 mechanism or tongs which engage the skelp or flat plate near the forward end of the bending die to draw it therethrough. The gripping mechanism or tongs 3 is of the usual construction and operates upon the 15 bench 4 as shown. The mechanism for drawing the skelp through the bending die may be of the usual form and comprises a suitable sprocket chain 5 to which one end of the gripping mechanism is connected by 20 means of the rod 3^a. The sprocket chain may be driven by any suitable source of power, such as a motor or the like.

The tube forming devices which coöperate with the bending die may be supported 25 in any suitable manner, and for the purpose herein I show a frame 1^a. The tube forming devices are successively mounted in said frame, that is to say, one tube forming device 6 which delivers an initial blow to the 30 skelp is positioned near the entrance end of the bending die, and the other tube forming device 7 over which the skelp is drawn is located intermediate the length thereof. Suitable double acting pistons operable in 35 cylinders 8 and 9, respectively, control these tube forming devices. The movement of the pistons may be controlled by any suitable source of pressure. In the cylinder 8 which controls the tube forming device 6 the 40 said pressure medium is admitted upon either side of the piston through the openings 10 and 11, respectively. In the cylinder 9 which controls the other tube forming device the pressure medium is likewise admitted to either side of the piston through 45 the openings 12 and 13. The pressure medium supply and discharge may be controlled through any suitable valve mechanism, preferably of the four-way type of 50 usual construction, (not shown). By this general construction it will be seen that the relative movement of the tube forming devices will be positively controlled in a minimum amount of time when they are lowered 55 and raised.

The relative adjustment of the cylinders 8 and 9 is shown as comprising spaced frame sections 14 and 15. The frame section 14 comprises a U-shaped member 16 having positioned therein frame sections 17 and 18. These frame sections 17 and 18 are in the nature of filling blocks and serve to rigidly support the cylinders within the frame. The filling block 18 is shown as provided 60 with extensions 19, having openings therein

which register with similar openings in the U-shaped member 14. Bolts 20 pass through these registering openings. To the free ends of the U-shaped member 14 the depending arms 21 of a U-shaped member 22 are attached. The U-shaped member 22 depends from the upper portion of frame 1^a, as shown. The frame section 15 is of similar construction to that just described and comprises a U-shaped member having filling frames 23 and 24. The filling frame 23 supports the cylinder 8 and the frame 24 the cylinder 9. As shown, the filling frame 24 is provided with extensions 25 having openings therein which register with similar 70 openings provided in the side arm of the U-shaped member of the frame 15. Bolts 26 secure the filling frame 24 to the U-shaped member. The free ends of this U-shaped member are secured to the frame 1^a as 75 shown.

The cylinders are further supported in the upper portion of the frame 1^a by the vertically extending rods 27 which pass through a slotted bar 28 secured to the frame 1^a. Nuts 29 are threaded on the rods above and below the said bar 28 and serve to hold the cylinders in adjusted position.

By this construction it will be seen that the respective cylinders 8 and 9 can be relatively adjusted within the frame 1^a, thereby providing for a corresponding positioning of the tube forming devices with relation to the bending die. The tube forming device or initial blow member 6, which is controlled by the cylinder 8, is provided with a forming head 6^a the under-side of which is of a substantially corresponding curvature to that of the bending die at or about its entrance end. This tube forming device 6 is secured to the screw-threaded end of the piston rod 30. A suitable guide, comprising a rod 31 is attached to the piston rod by means of a nut 32. This guide rod extends upwardly and passes through apertured lugs 33, formed on the cylinder 8. The purpose of this guide is to render the tube forming device stable and non-rotatable in its reciprocatory movement. The intermediate positioned tube forming device 7 over which the skelp is drawn and which is controlled by the cylinder 9, is carried by the piston rod 34. This piston rod 34 is slotted at its lower end at 35 and receives the end 36 of the pivotally supported arm 37. This arm 37 is reduced at one end, as at 38, and receives the tube forming device or "pipe ball" 7^a which is rotatably secured thereto by the nut 39. The opposite end 36 of the arm 37 is slotted as at 40 and contains a spring 41 interposed between the end of said arm and the pivotal connection 42 which supports the tube forming device 7. Suitable lugs 43 are provided to extend into the ends of the spring, and pins 44 are in 100 105 110 115 120 125 130

serted through said lugs between the end coils of the spring for retaining the said spring in position. By this construction it will be seen that the spring can be readily 5 removed and a new one inserted. The lug 45 is provided on the end 36 of the arm 37 and abuts against a nut 46 screw-threaded upon the piston rod 34. Between the nut 46 and a similar nut 47 a guide member 48 10 is secured. The guide member 48 carries a rod 49 which reciprocates within the guiding lug 50 formed on the cylinder 9. The purpose of this guiding device is to maintain the tube forming device 7 in a stable 15 position and free from rotation while being raised and lowered. A stop lug 51 is provided on the arm 37 and limits the horizontal movement of the tube forming device or "pipe ball" within the bending die, as 20 shown in Fig. 2.

The pivotal connection 42 comprises a block 52 upon which the arm 37 moves. One of the lugs 43 is carried by this block 52, as shown in Fig. 6. A bolt 53 passes 25 through this block 52 and registering apertures provided in the piston rod 34.

In operation the flat plate is fed over a suitable device 54 into the flaring or bell-shaped end of the bending die 1. As the 30 end of the flat plate or skelp passes beneath the tube forming device 6 it is given a slight bend corresponding to the curvature of the bending die and the coöperating underside of the forming head 6^a. The traveling gripper 3 is moved through the bending die and attached to the end of the skelp or flat plate after it has been fed within the flaring end 35 of the said bending die. The connection 3^a of the traveling gripper is now attached to the sprocket chain 5 and the skelp is drawn through the bending die. After the tube 40 forming device 6 has given the initial curvature to the skelp it is withdrawn therefrom. The tube forming device 7 is now lowered 45 upon the flat plate in timed relation thereto and as the skelp is drawn onward through the die the forming head or "pipe ball" 7^a is drawn within the bending die and the skelp which has now been tubularly formed at 50 one end, as shown in Fig. 2. The piston rod 34 which carries the tube forming device 7 is moved a predetermined distance downwardly to insure the proper horizontal co-operation of the "pipe ball" 7^a within the 55 bending die. When the formed tube is withdrawn from the bending die the spring 41, which has been compressed during the drawing of the tube, will now act to withdraw the tube forming device 7 from within the 60 bending die. The return of the piston rod 34 in an upward direction permits of the arm 37 assuming its relatively normal position, as shown in Fig. 6, with the lug 45 bearing against the nut 46.

65 From the foregoing it will be obvious that

an efficient mechanism has been provided wherein certain economic advantages can be obtained, and a rapidity of operation secured for an increased output of the product. It will also be seen that the successive 70 coöperation of the respective tube forming devices within the bending die in a positive manner permits of a more uniform bending of the skelp.

What we claim is:

1. A metal bending mechanism of the 75 class described including in combination, a bending die, a movable tube forming device coöperating with said bending die and located near the entrance end thereof, another movable tube forming device coöperating with the said bending die located intermediate the length thereof, and means for operating said tube forming devices.

2. A metal bending mechanism of the 80 class described including in combination a bending die, a movable tube forming device positioned at one end of said bending die, means including a piston for operating said tube forming device, another tube forming 85 device positioned intermediate the length of the bending die, and means including a piston for operating said second mentioned tube forming device.

3. A metal bending mechanism of the 90 class described, including in combination, a bending die, a movable tube forming device coöperating with said die, means for raising and lowering said tube forming device and means including a sliding connection 95 for withdrawing the said tube forming device from within the bending die.

4. A metal bending mechanism of the 100 class described including in combination a bending die, a tube forming device coöperating with said die, means including a piston rod for raising and lowering said tube forming device and means including a spring for withdrawing said tube forming device from within the bending die.

5. A metal bending mechanism of the 105 class described, including in combination a bending die, a plurality of coöperating tube forming devices for said bending die, guides for said tube forming devices, and means for raising and lowering the said tube forming device upon the aforesaid guides.

6. A metal bending mechanism of the 110 class described, including in combination a bending die, a plurality of coöperating tube forming devices for said bending die, and means for adjusting said tube forming devices with relation to each other.

7. A metal bending mechanism of the 115 class described, including in combination a bending die, a plurality of coöperating tube forming devices for said die, and means for adjusting said tube forming devices with relation to each other and to the bending die.

8. A metal bending mechanism of the 120 class described, including in combination a bending die, a plurality of coöperating tube forming devices for said die, and means for adjusting said tube forming devices with relation to each other and to the bending die.

class described, including in combination a bending die, a coöperating tube forming device for said bending die, a guide for said tube forming device, means for raising and lowering the said tube forming device upon the bending die, and means for withdrawing the tube forming device from within the bending die.

9. A metal bending mechanism of the class described, including in combination a bending die, a plurality of successively operated coöperating tube forming devices for said bending die, means for adjusting the relative position of said tube forming devices, guides for said tube forming devices, means for raising and lowering the said tube forming devices upon the bending die, and additional means for moving one of said tube forming devices within the bending die.

10. A metal bending mechanism of the class described including in combination a bending die, a coöperating tube forming device for said bending die, said tube forming device comprising a positive controlled reciprocating piston rod, an arm pivotally connected to said piston rod, and a tube forming head carried by said arm.

11. A metal bending mechanism of the class described including in combination a

bending die, a coöperating tube forming device for said bending die, said tube forming device comprising a positive controlled reciprocating piston rod, an arm pivotally connected to said piston rod, a tube forming head carried by said arm, and means including a sliding connection for moving the said arm upon the aforesaid pivotal connection.

12. In a metal bending device of the class described, the combination with a bending die, of a plurality of successively arranged tube forming devices, and means including a plurality of pistons for independently operating the said tube forming devices.

13. In a metal bending device of the class described, the combination with a bending die, of a vertically movable tube forming device, another tube forming device horizontally movable within the bending die and means for operating said tube forming devices.

In testimony whereof we affix our signatures in the presence of two witness^s.
